FIG. 1 is a perspective view of a nail buffer showing my new design;

FIG. 2 is a bottom plan view;

FIG. 3 is a side elevation view; and

FIG. 4 is an end elevational view.

The characteristic feature of my design resides in the combination in a nail buffer of a nail buffer portion of the configuration shown and a body portion being substantially rectangular in plan configuration and having downwardly and outwardly tapering side and walls.

I claim:

The ornamental design for a nail buffer, as shown and described.
